ROOF STRUCTURE

Application filed July 11, 1928. Serial No. 291,710.

In this specification, and the accompanying drawing, we shall describe and show a preferred form of our invention, and specifically mention certain of its more important objects.

We do not limit ourselves to the forms disclosed, since various changes and adaptations may be made therein without departing from the essence of our invention as hereinafter claimed; and objects and advantages, other than those specifically mentioned, are included within its scope.

The character of a house is largely exemplified in its roof. It should be efficient and economical. A steep roof covered with composition shingles, beautifully proportioned simulating tile gives the house a decidedly ornamental character. One often does not realize how important the roof is in the 20 position of most houses. This invention therefore pertains to an essential architectural feature.

This invention relates to roofs and improved means for constructing the same and 25 it is an object of this invention to provide in conjunction with the improved means for securing durability; a structure which will also possess beauty and ornateness, thus enhancing general styles of existing architecture 30 now in vogue.

It is a special object of this invention to provide a roofing applicable to certain types of old existing roofs.

It is a further object of the invention to 35 simulate certain classes of roofs as for instance that of Spanish tile.

Tile roofs are expensive to construct, for in addition to the heavy timbers required in supporting them, the tiles are expensive 40 themselves and the cost of labor required in laying them is quite excessive as the labor has to be skilled on account of their particular mode of application.

It is a still further object of the invention 45 to provide a roof simulating that as set forth in the preceding paragraph, in which a plurality of contour members are arranged in spaced relation over which are laid composition shingles or the like to form the convex 50 side of the tile and alternating between said

contour members are placed composition shingles which are bent in concave fashion, forming the valley shingles, all the shingles being fastened by prongs punched from the metal forming the contour member.

It is a still further object of the invention to use the fastening prongs aforesaid to maintain alignment of the shingles as they are laid in successive courses to the weather in producing a tile effect.

Still another object of the invention is in the added strength supplied by the contour members in view of the lightness of the materials involved and also the quality of their fireproofness.

These as well as other objects which may hereinafter appear will be set forth more fully in the description following, when viewed with the accompanying drawings wherein:

Figure 1 is a perspective view of a portion of a roof involving the present invention.

Figure 2 is a fragmentary portion of one of the contour members illustrating the position of the prongs before application of the roof, and

Figure 3 is a perspective view of a composition shingle used to illustrate by its application to the contour members in Figure 1 the simulation of Spanish tile.

Referring to the drawings, particularly to Figure 1, a portion of a roof is shown which is composed of a plurality of horizontally spaced contour members 1, to which are fastened the overlying composition shingles 2 and 2a.

Herein is specified specifically the use of composition shingles as illustrated in Figure 3 on account of their flexibility, their ability to adhere when subjected to the scorching rays of the meridian sun, their quality of fireproofness and the various color combinations to be had.

Yet it is to be understood the invention is not to be limited to their use entirely, as a tile effect may be obtained by using a similar composition, as for example, long strips, overlapping it in a manner to simulate the joints of tile and cementing it together as is

ordinarily done in flat composition roof not embodying the use of a contour member.

The contour members 1 are constructed of a light gage metal, and may be coated with 5 suitable non-corrosive coating. They may be applied to the roofing members 3 in any convenient and practical manner.

The roofing members 3 are the usual sheathing strips applied to roof rafters 4, such construction being that ordinarily used in constructing roofs and is a roofing construction well understood. They in the present instance, however, not only support the contour members but aid in supporting the concave portion 9 of the composition shingles forming the valleys spaced therebetween.

On account of the lightness of the contour members and the composition shingles, no reinforcing is necessary in the application of 20 this roof to existing structures, the same applying to new structures as well, yet the contour members themselves have strength which adds stiffness to the roof.

The contour members are pressed in a 25 semi-cylindrical fashion, having a convex surface, the curvature of which is similar and simulating that of Spanish tiles. They have a flanged edge 5, 5 on either side whereby to fasten the contour member rigidly to 30 the sheathing strips 3. They are spaced in fixed relation as will be more fully herein-after described and extend longitudinally upwardly and downwardly of the roof.

Furthermore the contour members extending 35 longitudinally upwardly and downwardly of the roof, not only serve the purpose of simulating tile ridges but add counter-strength to the roof and at the same time decreasing the temperature absorbing qualities of the roof.

Integral with said contour members are provided means for connecting the composition shingles and contour members together, said means consisting of prongs 6, 7 and 8 45 punched from the metal, said prongs being adapted to be bent over the sides and ends of the shingles as fully illustrated in Figure 1, thereby clinching the shingles to the contour members.

The prongs are desirably arranged in sets of three, the central prong 7 of each set having a claw 7a. Said prong 7 being adapted for bending down longitudinally upon the crest portion of the convexity of the sheet metal contour member from which it is struck up and the prongs 6 and 8 are disposed laterally to said prong 7, said prongs 6 and 8 being adapted to be bent down laterally over the side edges of the shingles 9. The prongs 60 7 are adapted for bending over the end edges of the flexible bridging shingles 2a and piercing the same with the claw 7a. It is obvious the prongs 6 and 8 also could be provided with claws 7a.

In laying the shingles after the contour

members 1 have been spaced, the shingles 2 forming the valleys of the first and lower course are bent in concave fashion so that the bottom portion of the shingle at its mid-width will rest upon the sheathing strip as indicated by the numeral 9.

The prongs 8 are then bent over the sides thereof holding it in place. It is obvious, that were the shingles made into a continuous strip, the prongs would have to pierce the material.

The bridging shingles 2a are then superposed over the valley shingles 2 and fastened in place by means of the center prong 7 and its claw 7a as indicated by the numeral 10 and this center prong should be set just slightly in advance of the prongs 6 and 8 so as to be able to clinch over the end of the shingle 2a without cutting thereinto, while the prongs 6 and 8 clinch over the side edges 85 of the valley shingle 2 lying therebeneath.

The prong 7 with its claw 7a as shown at 10, clinches the upper edge of the bridging shingles 2a to the contour members 1 and the prong 7 together with the consecutive courses 90 of over lapping valley shingles 2 resting partly upon it restrain the remaining portion from curling up. Obviously the prong 7 may also be utilized to preserve alinement of the shingles when desired.

It will be noted that only every other center prong is used in clinching, yet the same is provided at the same time to avoid the use of an extra die.

The succeeding courses of shingles are laid 100 in like manner and the number laid to the weather will be determined by climatic conditions and the taste of the architect.

The heat from the sun soon amalgamates 105 the entire structure in a composite mass.

Any rain or moisture getting on the roof will be carried from one row of shingles to the next so that it will not pass under the shingles. Even where water might accumulate in some quantity on the roof, it would hardly be deep enough to pass up under and over the edges of the shingles forming the valleys which are overlapped by the superposed shingles.

Usually this water shedding is determined 115 by the pitch of the roof. The prongs are secured beneath the shingles so that none are accessible to the moisture.

The shingles 2 and 2a being arranged in rows in overlapping fashion, as shown in Figure 1, form an ornamental appearance and relieves the monotony of an otherwise plain surface roof, and when viewed at a distance closely simulates the appearance of 120 a tile roof.

In breaking the joints between shingles or strips of roofing after the scheme herein promulgated, it will be clear that the joints can be easily, quickly and efficiently made without the use of nails exposed to the weather and 130

the adhesive properties of the shingles insure a tight seam at the overlapping joints and a waterproof seam is insured without the use of cement or other adhesive material.

5 A roof as herein set forth will furnish a more elaborate and pretentious setting when silhouetted against a dark background and intercepting all the shifting lights and shadows.

10 A beautiful, ornamental and durable roof may thus be produced at a very nominal cost.

We claim:

1. In a roofing structure, the combination with flexible shingles, of an elongated 15 concavo-convex sheet metal shingle supporting member having at the crest of its convexity a prong struck up which is adapted to be bent down longitudinally of said member over the end edge of a shingle and a side 20 prong at each side of the first mentioned prong, said side prong being adapted for bending down toward the long edge of said member over the side edge of another shingle.

2. As an article of manufacture, a shingle 25 supporting contour member consisting of an elongated strip of sheet metal having an arched portion throughout its length and a foot flange along each side edge thereof, and prongs extending outwardly from the convexity of said arch, said prongs being punched from the metal, some of said prongs being bendable axially of said member and others being bendable transversely thereof.

3. In combination with a supporting structure, a plurality of elongated contour members in parallel spaced formation having an arched portion throughout their mid-width and a foot flange along each side thereof, valley shingles overlapping the adjacent 40 edges of said contour members, and bridging shingles covering the space intervening between said valley shingles and overlapping the latter shingles, prongs projecting outwardly from the arched portion of said contour members and bendable axially over the side edge portions of said valley shingles and transversely over the end edge portion of said bridge shingle.

4. As an article of manufacture, a shingle- 50 supporting contour member having an arched portion throughout its mid-width and a foot-flange along each side thereof, and prongs extending outwardly from the convexity of said arch, some of said prongs being bendable axially of said member and others being bendable transversely thereof, some of said prongs having terminal claw portions to project into the shingles.

In testimony whereof, we hereunto affix our 60 signatures to this specification.

GUY EDGAR LIVINGSTON.

WILLIAM HENRY CLAY NESS.
